(57) **CLAIM**

We claim the ornamental design for a winch line eye, substantially as shown and described.

DESCRIPTION

FIG. 1 is a front isometric view of a winch line eye, showing our new design.

FIG. 2 is a front elevation view of the winch line eye of FIG. 1; and,

FIG. 3 is a rear elevation view of the winch line eye of FIG. 1.

The areas shown in light gray in the figures show environment, and form no part of the claimed design.
